UNITED STATES PATENT OFFICE

NOAH S. HARTER, OF WAUKEGAN, ILLINOIS, ASSIGNOR TO KING BOAT COMPANY, A COPARTNERSHIP CONSISTING OF NOAH S. HARTER, ERNEST H. HARPER, A. F. BEAUBIEN, HARRY CHAPMAN, AND WALTER BILHARS

COLLAPSIBLE PONTOON FOR BOATS AND THE LIKE

Application filed May 19, 1927. Serial No. 192,588.

This invention relates to improvements in pontoons for boats and similar craft, and more particularly to collapsible pontoons, both of the fixed and removable variety, 5 adapted to be automatically filled with air upon extension, and to be mounted on the gunwales and bow of a boat or the like, to increase the buoyancy and prevent the sinking of the same, in addition to greatly adding 10 to the stability of the craft.

The present invention provides collapsible pontoons for boats which may be built in or are removable from a boat or similar water craft, which provide obvious advantages over 15 the well known type of rigid, built-in, non-collapsible pontoons, and which are especially adapted for use with collapsible portable boats. When used on a boat in calm water a device of the class described may be 20 collapsed so as not to interfere with the maneuvering or speed of the boat, and in case of a rough sea or sudden storm, may be extended by a single jerk on a pull cord, in which extended position it will give added 25 buoyancy and stability to the craft, effectively preventing accidental overturning or sinking of the same.

It is accordingly an object of this invention to provide collapsible pontoons for a 30 boat or the like, which are automatically filled with air upon extension of the same.

Another object of this invention is to provide removable pontoons adapted for easy and quick installation on a water craft. 35

A further object of this invention is to provide collapsible pontoons adapted for installation on the sides or bow of a boat or the like.

A still further object of this invention is to 40 provide boat pontoons which may be rapidly collapsed or extended by a single tug on a pull cord.

Other and further important objects of this invention will be apparent from the dis- 45 closures in the specification and accompanying drawings.

This invention (in a preferred form) is 50 illustrated in the drawings and hereinafter more fully described.

On the drawings:

Figure 1 is a perspective view of a collapsible boat fitted with devices embodying principles of the present invention.

Figure 2 is a plan view of a boat fitted with the devices of Figure 1. 55

Figure 3 is a fragmentary vertical sectional view taken substantially along line III—III of Figure 2.

Figure 4 is a horizontal sectional view taken substantially along line IV—IV of 60 Figure 3.

Figure 5 is a vertical sectional view similar to Figure 3 showing a removable form of the device.

Figure 6 is a fragmentary view in elevation 65 taken from the left of Figure 5.

Figure 7 is a sectional view of a portion of the device, namely, a stop plug.

Figure 8 is a plan view of a modified form of the present invention, showing the same 70 secured to a boat.

Figure 9 is a horizontal sectional view, with parts omitted, taken substantially along line IX—IX of Figure 8.

Figure 10 is a vertical sectional view taken 75 substantially along line X—X of Figure 9.

Figure 11 is a fragmentary view in elevation taken from the left of Figure 10.

As shown on the drawings:

The illustrated embodiment of the present 80 invention is shown attached to a boat of the collapsible portable type but, of course, it is equally adapted for attachment to any form of boat.

The reference numeral 1 indicates a boat 85 which is encased by an impervious covering 2. Secured to the sides of the boat 1 is a plurality of collapsible pontoons 3 which are substantially identical in construction. In Figure 2, the full lines show the pontoons 3 90 in their inflated or extended form, and the dotted lines show the pontoons collapsed. It is to be noted that in their collapsed positions, the pontoons adhere substantially to the sides of the boat 1 and form themselves 95 accordingly, whereby they do not detract in any degree from the speed or maneuvering of the boat.

Each of the pontoons 3 comprises an impervious and flexible casing or covering 4 100

which is attached as shown at 5 or in any desired manner to the covering 2 of the boat 1 and which encloses an air chamber 6. Within the chamber 6 there is provided a plurality of angularly bent supporting rods or braces 7 having inwardly bent tips 8 thereon, which tips 8 are loosely engaged by straps 9 secured to the covering 2 of the boat 1. A flexible strip 10 interconnects the braces 7 so that the braces may be actuated simultaneously. To limit the pivotal movement of the braces within the straps 9 a flexible tension strip 11 is secured to one of the braces and to the covering 2 as shown at 12. To elevate the braces 7 into their extended position a pull cord 13, preferably of extra heavy or double thickness canvas, is secured to one end of the interconnecting strip 10, or if desired may be made integral therewith, and for dropping the braces into their collapsed position, a pull cord 14 is fastened to the other end of the interconnecting strip 10. In order that the pontoon, when in its inflated or extended position, may have a substantially right angular portion at one end, an end brace 7^a is provided which is secured to one of the braces 7 by a stiffened strip 15. The pull cords 13 and 14 are each connected to similar stop plugs 16 and 16^a, respectively, each of which is adapted for engagement with a flange 17 extending through an aperture 18 in the casing 4, which flange 17 has an aperture 19 therein, the aperture 19, of course, being covered by the water-tight engagement of the stop plug 16 connected by the flange 17.

The stop plug 16 and the flanges 17 are identical with the stop plugs and flanges set forth and described in my co-pending application for United States Letters Patent for collapsible air chamber seat, filed May 19, 1927, Serial No. 192,586, and so will not be further described herein.

In operation each of the pontoons 3 are identical, the basic principle being substantially similar to that disclosed in my above identified copending application. Assuming it is desired to collapse the pontoons from their inflated or extended position as shown in Figures 2 to 4, inclusive, the stop plug 16^a is removed and the pull cord 14 given a slight tug or jerk, thereby actuating the braces 7 and causing the same to pivot within the straps 9 and assume a horizontal position as shown by the dotted lines in Figure 4, the casing 4 falling down upon the collapsed braces and held in this position by the end brace 7^a. The air contained in the chamber 6 passes out through the aperture 19 left uncovered by the removal of the stop plug 16^a. The stop plug is then replaced to prevent water from entering the collapsed pontoon. To adjust the device to its extended position it is only necessary to remove the stop plug

16 and raise the braces 7 simultaneously by a slight pull on the pull cord 13, air simultaneously entering the chamber 6 through the aperture left by the removal of the stop plug, after which the stop plug 16 is replaced. 70

It is to be noted that the braces 7 when in their extended position are not exactly normal to the sides of the boat 1, but are slightly inclined to the pull cord 13 as shown in Figure 4. Further inclination in this direction is prevented by the tension strip 11. In this position the braces are adapted to withstand any sudden jars or exterior pressure, to which the pontoon may be subjected when in use, 80 without collapsing. 75

Figure 5 illustrates a device of the class described herein which is adapted to be removably mounted to a boat or the like. The only difference between this form and the previously described form of this invention, is the addition of a strip 20 of impervious material which is secured on one side to the covering 4 as at 21, forming a water-tight joint, and at the other side is held in clamped relationship with the covering 4 by rivets 22 which secure both the strip 20 and the covering 4 to stiffened hangers 23, which hangers are adapted to engage over the gunwale of a boat. The strip 20 in this form of the invention supports the straps 9 and is secured to it one end of the tension strap 11. 90

Fastened to the covering 2 of a boat 1 as at 24, is a relatively narrow strip 25 of impervious material adjacent to which the casing 4 terminates. As shown in Figure 6, both the casing 4 and the strip 25 are apertured and provided with eyelets 26 to accommodate the lacing 27 which holds the pontoon in tight engagement along its lower edge with the boat 1. The operation of this form of the invention is the same as that of the previously described form. 100

Figures 8 to 11 inclusive show a modified form of this invention which consists of a collapsible pontoon 28 adapted to be removably secured over the bow of a boat 1 to form substantially a buoyant cabin deck. In this form of the device there is shown an impervious casing 4 enclosing an air chamber 6 and extending downwardly substantially perpendicular, when in use, as at 29, which extensions are provided with apertures and eyelets 26 to accommodate the lacing 27 which secures the pontoon 28 at each side to a relatively narrow strip 25 secured to the casing 2 on the boat 1. The bottom of the pontoon is formed by a sheet 30 of similar impervious material downwardly bent at each side as at 31 and attached to the casing 4 in any desired manner to form a water-tight joint. This sheet 30 has affixed thereto straps 9 which loosely engage over inwardly turned ends 8 of braces 32 which braces are substantially arcuate in form, a flexible strip 10 in- 110

120

125

130

terconnects the braces 32 and is affixed to each brace individually by a strap 33. The interconnecting strip 10 is continued at one end to form a pull cord 34 which is connected to 5 a stop plug or air valve 35, and is continued at the other end to form a pull cord 26 which is connected to stop plug 35^a.

Stop plugs 35 and 35^a are identical to stop plugs 16 and 16^a previously described. A 10 tension strip 37 is secured to the interconnecting strip 10 adjacent the pull cord 36 as shown at 38, and is also secured to the sheet 30 as at 39. The operation of this form of the invention is substantially the same as in 15 the previously described forms.

To collapse the pontoon 28 stop plug 35^a is removed and the braces 32 actuated through the pull cord 36, whereby the braces are pivoted within the straps 9 and assume a 20 horizontal position as shown by the dotted lines in Figure 9, and the casing 4 will assume a position adjacent thereto. Stop plug 35^a is then replaced to exclude water from the air chamber 6. To adjust the device to its 25 inflated or extended form stop plug 35 is removed and the braces elevated through the pull cord 34, after which the stop plug 35 is replaced.

It is to be noted also in this form, that the 30 braces 32 are slightly inclined from the vertical, this inclination being limited by the tension strip 37, to withstand pressure exerted upon the top of the casing 4.

The present invention is shown in this application as attached to a portable collapsible boat, but obviously may be attached to any boat. In the removable form strips 25 may be glued or tacked to the sides of any wooden or metal boat, and the device would function 40 in the previously described manner.

From the foregoing it is apparent that I have provided novel safety pontoons which are quickly adjustable for use in case of emergency and which may be collapsed when 45 not needed into a compact form which does not interfere with any desired maneuvers of a boat to which they are attached. The invention herein described will effectively prevent the accidental overturning or sinking 50 of a boat, and will permit a waterlogged boat to be safely brought ashore by the occupants of the boat.

I am aware that many changes may be made and numerous details of construction 55 may be varied through a wide range without departing from the principles of this invention and, therefore, do not purpose limiting the patent granted hereon, otherwise than necessitated by the prior art.

60 I claim as my invention:

1. In a device of the class described, a sheet of material impervious to liquids, a casing of material impervious to liquids secured thereto and enclosing an air-chamber, 65 braces pivotally secured to said sheet and

adapted to abut the inner side of said casing when pivoted outwardly, means for limiting the movement of said braces, and means for actuating said braces.

2. In a device of the class described, an 70 impervious casing having a pair of apertures therein and adapted to be mounted on the exterior of a boat, stop plugs in said apertures, interconnected braces pivotally mounted within said casing, a pull cord for actuating said braces to expand said casing, and a pull cord to actuate said braces to collapse said casing, each of said cords being secured to one of said plugs.

3. In combination, a floatable member, a 80 flexible strip secured thereto, a casing having an air chamber therein, a flexible strip on said casing, and means for connecting said strips to secure said casing to said floatable member.

4. In a device of the class described, a 85 collapsible casing having ports leading to an air chamber therein, means for attaching said casing to the exterior of a floatable member, means within said casing for expanding the same, means for actuating said expanding means, and means associated with said actuating means for sealing said ports.

5. In combination, a floatable member, a 90 flexible strip thereon, a collapsible casing enclosing an air chamber, means for expanding said casing and retaining the same in expanded position against pressure thereon, means for collapsing said casing, a flexible strip on said casing, and means for connecting said strips to removably secure said casing to said member.

6. In a device of the character described, 95 a casing formed of flexible material and housing an air chamber, means pivoted to the inner face of a wall of said casing, means for actuating said first mentioned means to cause the same to abut the opposite wall of said casing to expand the same, means limiting the movement of said first mentioned means to cause the same to assume a position slightly inclined from the vertical, and separate means for actuating said first mentioned means to collapse said casing, there being 100 ports in said casing to permit the ingress and egress of air thereto and therefrom.

In testimony whereof I have hereunto subscribed my name at Waukegan, Lake County, Illinois.

NOAH S. HARTER.
